UNITED STATES PATENT OFFICE

161,850

SPECTACLE CONTAINER

Fred J. Maier, Chicago, Ill.

Application October 4, 1950, Serial No. 12,443

Term of patent 14 years

(Cl. D57—1)

To all whom it may concern:

Be it known that I, Fred J. Maier, a citizen of the United States, residing at Chicago, in the county of Cook and State of Illinois, have invented a new, original, and ornamental Design for a Spectacle Container, of which the following is a specification, reference being had to the accompanying drawing, forming a part hereof.

Fig. 2 is a top plan view thereof; and

Fig. 3 is an end elevational view thereof.

The dominant features of my new design are shown in solid lines in the drawing.

I claim:

The ornamental design for a spectacle container, substantially as shown and described.

FRED J. MAIER.
